Primary Examiner — Bridget L Eland(74) *Attorney, Agent, or Firm* — Oppedahl Patent Law Firm LLC(57) **CLAIM**

The ornamental design for a mobile phone, as shown and described.

DESCRIPTION

1.1 is a front view of a mobile phone showing the new design;

1.2 is a back view thereof;

1.3 is a left view thereof;

1.4 is a right view thereof;

1.5 is a top view thereof;

1.6 is a bottom view thereof;

1.7 is a front perspective view thereof; and

1.8 is a back perspective view thereof.

The broken lines shown in the drawings illustrate portions of the mobile phone and form no part of the claimed design. The dot-dash broken lines illustrate the boundary of the claimed design and form no part thereof.

1 Claim, 8 Drawing Sheets(56)
